US0D1056879S

(12) **United States Design Patent** (10) **Patent No.:** **US D1,056,879 S**
(45) **Date of Patent:** **** Jan. 7, 2025**

(54) **COMBINED WIRELESS EARPHONES AND CASE**

(71) Applicant: **Shenzhen Huanfang Technology Co., Ltd.**, Shenzhen (CN)

(72) Inventor: **Huan Liao**, Shenzhen (CN)

(**) Term: **15 Years**

(21) Appl. No.: **29/963,823**

(22) Filed: **Sep. 19, 2024**

(51) **LOC (15) Cl.** **14-01**

(52) **U.S. Cl.**

USPC **D14/223**; D13/108; D3/274

(57) **CLAIM**

The ornamental design for a combined wireless earphones and case as shown and described.

DESCRIPTION

FIG. 1 is a perspective view of a case, of the combined wireless earphones and case, showing my new design, the case is shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of earphones, of the combined wireless earphones and case, shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of a combined wireless earphones and case in an open position thereof.

The broken lines in the drawings depict portions of the combined wireless earphones and case that form no part of the claimed design.

1 Claim, 17 Drawing Sheets
